UNITED STATES PATENT OFFICE

WALTER COX, OF METHUEN, MASSACHUSETTS, ASSIGNOR TO GARDNER W. PEARSON,
TRUSTEE, OF LOWELL, MASSACHUSETTS

ADJUSTABLE RING HOLDER AND SPRING WASHER

Application filed March 13, 1930. Serial No. 435,596.

This invention relates to what may be called ring frames such as are used in the manufacture of yarn and thread usually known as spinning frames or twisting frames.

In such frames there is a row or there are two rows of metal guide rings around which a wire guide known as a traveler moves in the process of delivering roving or yarn to a bobbin and in the process of spinning or twisting it and winding it on the bobbin.

In such frames, there are usually a series of spindles upon which or with which revolve the bobbins upon which the spun or twisted thread or yarn is to be wound.

In order that the best results may be obtained, the axis of the guide or driving spindle should always coincide with the center of the guide ring whether the guide ring is stationary or moves up and down.

It is often desirable also to change the size of the rings from larger to smaller or vice versa and it is always desirable to have the rings so attached to the ring rail that they can readily be removed and replaced by others.

This invention provides means whereby the ring rail or what serves the function of the usual ring rail is so made and is so provided with ring supporting means that each ring can be adjusted in all directions back and forth and right and left to correctly center it on the spindle.

This is very important because if the spindle is off center, the roving or yarn is much more likely to break.

In my preferred form, I also provide means between the ring and its supporting plate whereby the parts can be quickly assembled or disassembled and rings of various sizes can be substituted one for the other.

In any form of my device I can use the standard form of traveler holding ring without alteration and can readily remove and replace such ring. In the preferred form without changing the rail or support for the rings, by using a split washer I can change the size of the rings.

The principal advantage of my device,

however, is the fact that in my preferred type of supporting plate, by loosening two screws or bolts I can center the ring on the spindle very quickly and then by tightening the screws or the nuts on the two bolts 55 fix it in the correct position.

By my arrangement of clamps, ears, and bolts, the bolt heads are at the top and can easily be reached while the clamping screw or screws preferably project through the 60 side of the plate where they can be easily and quickly reached with a screwdriver for tightening or loosening.

Instead of adjusting bolts, I can use adjusting screws and my device can also be 65 used in a drawing frame as well as a spinning or twisting frame.

Any one of my ring holding assemblies with its one ring can be quickly removed 70 without affecting the others.

In the drawings, Fig. 1 is a diagrammatic elevation from the front of a spinning or twisting frame showing a rail with the device attached.

Fig. 2 is a plan view of a single ring held 75 in place by a washer and supporting plate.

Fig. 3 is a sectional elevation looking from the right on the line 3—3 of Fig. 2.

Fig. 4 is a sectional elevation enlarged looking from the right on the line 4—4 of 80 Fig. 1 showing a preferred form of rod support.

Fig. 5 is a plan view of a supporting plate with a different size of washer and for a different size of ring.

Fig. 6 is a view similar to Fig. 5 showing a supporting plate with no washer, but supporting a ring directly.

Fig. 7 is a plan view showing a different type of rod supports.

Fig. 8 is a detail elevation partly in section showing a modification of a clamp.

Fig. 9 is a detail sectional elevation of a simplified type of clamp assembly.

In the drawings, R represents the frame 95 of a ring spinning or twisting device or any other textile machine in which, as guides for travelers, a series of rings are supported by some sort of rail.

S, S represent rod supports each of which 100

as shown comprises the arms 1 and 2 connected at 3 and as shown in Fig. 1 supported by the vertical rods 4—4 which form part of the general means T by which said supports S, S carrying the rods A and B are moved up and down.

The rods A and B are carried respectively by the arms 1 and 2 and means to move them, T, may include levers such as 7 of 10 the type similar to those shown in my application for United States Letters Patent pending herewith Serial No. 425,867, filed Feb. 4, 1930.

Slidable on each rod A and B are the 15 oppositely disposed clamps C and C' each comprising two members such as 10, 12 and 11, 13. Each set of members such as 10, 12 is grooved so as to receive and slide on a rod such as B and each has a bolt hole such 20 as 16 or 18 through which an adjusting bolt such as 14 or 114 can pass.

By means of such an adjusting bolt, the jaws such as 10 or 12 can be loosened or tightened and the clamps can be fastened 25 in any position along the rods A and B.

F represents a supporting plate which has in the center, a ring hole 20 and oppositely disposed ears 21 and 121 through each of which passes an adjusting bolt slot such as 20 22 or 122 which slots register with the bolt holes in the clamps C and C'.

14 and 114 represent the adjusting bolts for each clamp and these bolts serve two purposes.

35 By loosening the nuts such as 19 or 119, the clamps can be moved along the rods and the plate F can be moved back and forth between the rods thereby securing an universal adjustment.

40 In my preferred device, I use a split washer L which fits into or can be sprung into a ring hole 20, such washer terminating at 40 and 41 which allows it to be sprung into position.

45 By means of the two clamp screws 42 and 43 which pass through flange 24 of plate F and bear against the split washer on each side of the split, a traveler carrying ring such as H of a well known type can be inserted into the split washer L and firmly held in place by screwing up clamp screws 42 and 43.

K represents a traveler of any usual type. In Fig. 5, I show another size of split 55 washer M having ends 50 and 51 and only one clamp screw such as 52.

By using split washers of different sizes, a smaller ring N can be positioned and in every case the ring can be absolutely centered on the center of the spindle.

60 In many cases it is not necessary to use a split washer as the traveler guide ring can be held in position directly in the ring hole in the supporting plate as shown in Fig. 6. The ring P is of such size that it fits

easily in the ring hole 20 and is held in place by a clamp screw 25 which passes through the flange 24 in the same manner as 42, 43 and 52.

Instead of having a movable ring holding 70 rail, I may fit the ends such as 60 and 61 of the rods A and B in sockets such as 62 and 63 which are part of the permanent frame R and I may hold the rods A and B as by set screws 64 and 65. See Fig. 7. 75

As shown in Fig. 8, I may use adjusting screws such as 74 which pass through slots such as 22 in an ear such as 21 then through a hole 72 in one member 70 of a clamp such as V and into a hole 73 in the other member 71. By tightening or loosening this screw 74 the parts can be quickly adjusted.

As shown in Fig. 9, I can combine one clamp member or jaw with the supporting plate thus reducing the number of parts and 85 simplifying the construction.

In Fig. 9, 80 represents a lower jaw or clamp member having a recess 81 which fits partly around a rod support A and an adjusting hole 82 threaded to receive an adjusting member shown as a screw 74 which passes through the adjusting slot 22 in an ear 21, the parts being so arranged that when adjusting member 74 is tightened, the lower face 27 of ear 21 will nip rod A and 90 in cooperation with member 80 will fix the supporting plate in its adjusted position.

I claim:

1. The combination in a ring frame; of 100 rod supports; parallel rods carried thereby; means to move said supports and rods up and down; two oppositely disposed clamps each having an adjusting bolt hole and having jaws which engage and are slidable on a rod; a supporting plate having a ring hole 105 and oppositely disposed ears each having an adjusting bolt slot which registers with the adjusting bolt hole in a clamp; an adjusting bolt for each clamp which passes through said slot and hole; a split washer in 110 the ring hole; a traveler carrying ring carried by the washer; and two clamping screws which pass through the supporting plate and bear against the split washer on each side of the split. 115

2. The combination in a ring frame; of 120 rod supports; parallel rods carried thereby; two oppositely disposed clamps each having an adjusting bolt hole and having jaws which engage and are slidable on a rod; a supporting plate having a ring hole and oppositely disposed ears each having an adjusting bolt slot which registers with the adjusting bolt hole in a clamp; an adjusting bolt for each clamp which passes through said slot and hole; a split washer in the ring hole; a traveler carrying ring carried by the washer; and two clamping screws which pass through the supporting plate and 130

bear against the split washer on each side of the split.

3. The combination in a ring frame; of rod supports; parallel rods carried thereby; two oppositely disposed clamps each having an adjusting bolt hole and having jaws which engage and are slidable on a rod; a supporting plate having a ring hole and oppositely disposed ears each having an adjusting bolt slot which registers with the adjusting bolt hole in a clamp; an adjusting bolt for each clamp which passes through said slot and hole; a split washer in the ring hole; a traveler carrying ring carried by the washer; and clamping means which pass through the supporting plate and engage the split washer.

4. The combination in a ring frame; of rod supports; parallel rods carried thereby; two oppositely disposed clamps each having an adjusting bolt hole and having jaws which engage and are slidable on a rod; a supporting plate having a ring hole and oppositely disposed ears each having an adjusting bolt slot which registers with the adjusting bolt hole in a clamp; an adjusting bolt for each clamp which passes through said slot and hole; a traveler carrying ring positioned in the ring hole; and means to fix said ring in the ring hole.

5. The combination in a ring frame; of rod supports; parallel rods carried thereby; two oppositely disposed clamps each having a hole in jaws which engage and are slidable on a rod; a supporting plate having a ring hole and oppositely disposed ears each having an adjusting slot which registers with the adjusting hole in a clamp; an adjusting member for each clamp which passes through a slot and into a hole; and a traveler carrying ring positioned in the ring hole.

6. The combination in a ring frame; of rod supports; parallel rods carried thereby; a supporting plate positioned between the rod supports, said supporting plate having a ring hole and oppositely disposed ears each having an adjusting slot; two oppositely disposed clamp members each having an adjusting hole which registers with an adjusting slot in one of said ears, said members and the adjoining ears being slidable on a rod; an adjusting member for each ear and clamp member which passes through a slot and into a hole; and a traveler carrying ring positioned in the ring hole.

WALTER COX.
